HAROLD W. HOLLOWBECK, OF KIRKLAND, WASHINGTON, ASSIGNOR TO DURABLE MAT COMPANY, OF SEATTLE, WASHINGTON, A CORPORATION OF WASHINGTON

FLEXIBLE MAT

Application filed October 20, 1928. Serial No. 313,877.

This invention relates to flexible floor mats composed of a series of articulated links; and its object is the perfecting of mats of this character to render the same of more simple, 5 strong and inexpensive construction, and more efficient than other mats hitherto in use.

More specific objects and advantages of the invention will appear in the following 10 description.

The invention consists in the novel arrangement and combination of the link elements of a mat so that the assembly will constitute a truss-like formation providing 15 structural strength and rigidity against horizontal distortion, yet permit the mat being rolled upon itself to occupy a small space.

The greater part of the link elements, moreover, are disposed obliquely to both the 20 longitudinal and transverse axes of the mat, thereby facilitating the cleaning of shoes when moved in a direction rectilinear with respect to the mat to effect diagonal scraping action with respect to its link elements. 25 The mat links composing a mat are preferably made of a flexible or elastic material, good results being had by utilizing fabricated rubber obtained from discarded pneumatic tires.

30 The invention further consists in the novel construction, adaptation and combination of parts hereinafter described and claimed.

In the accompanying drawing,—

Figure 1 is a plan view of a mat embodying my improvements; Fig. 2 is a side edge view of the same; and Fig. 3 is a fragmentary horizontal section of the mat to larger scale, illustrating the manner of assembling and uniting parts thereof now preferred by me.

40 In carrying out the invention, I employ sections or rows, as A, B, and C, of links 5 and 6 arranged longitudinally of the mat, each of said links is an oblong shape in transverse section and is provided in its opposite 45 ends with apertures 7 (Fig. 3) to receive transverse rod elements 8 and 8¹ upon which links are strung in the successive rows and pivotally connecting the rows to one another.

The links above referred to are disposed in 50 zigzag order in each transverse row thereof;

and also in pairs, the complementary links of each pair being arranged in diverging relation successively in all of said rows from one end of the mat to the other.

The links are, furthermore, connected to 55 the rods to have the links of each pair contact with each other at corresponding ends of the respective pairs of links and be spread apart at their other ends spaced to accommodate therebetween the juxtaposed ends of 60 other pairs in the successive transverse rows of links longitudinally of the mat.

In the terminal rows—as A and C—however, annular spacing elements 9 (Fig. 1) are employed upon the bars 8¹ to position the 65 ends of adjacent links at distances apart to provide symmetrical longitudinal rows as 10, in what I term, "herring-bone" arrangement, throughout the length of the mat.

At each side of the mat is employed links 70 12, supplementary to and in lieu of obliquely arranged links 5 and 6.

These supplementary links are disposed in planes parallel with the longitudinal axis of the mat and serve two purposes: first, as tie 75 elements to prevent elongation of the mat structure to obviate lateral flexing of the obliquely arranged links 5 and 6; and, second, to provide approximately straight side rails of a mat frame, so to speak, composed so of parallel link elements to eliminate openings of irregular sizes and shapes along opposite sides of the mat.

The rods which unite the ends of the links, or the links and spacers 9, together in the 85 respective transverse rows and couple the same with the ends of adjoining rows of links, are advantageously made from a piece of wire which is bent into a rectangular shape, the side element 8 and 8¹ (Fig. 3) of which constitute the rods proper upon which the link and spacing elements are strung; the rod parts 8 and 8¹ integrally joined at one side of the mat by a tie element 8² and have at their other ends opposing terminals 8³ which 90 extend into a coupling sleeve 13.

14 and 15 represent bearing plates which are pierced, as at 7¹, to receive the rod elements 8 and 8¹ at the opposite side respectively of the link assembly, to protect the 100

outer links of the alternate rows thereof from being abraded by the rod structure.

My improved mat has an extended field of usefulness, of which may be mentioned—upon exposed stairs, porches and approaches to buildings; and also upon gang planks, decks and the bridges of marine vessels—due to the diagonal disposition of the mat links which prevents the sliding of a person standing or walking thereupon.

The construction of the invention and the manner of its use will, it is thought, be understood from the foregoing description.

What I claim, is—

- 15 1. A mat formed of sections consisting of transverse rows of obliquely disposed links longitudinally of the mat, and rods upon which said links are strung and which serve to hingedly connect the mat sections together,
- 20 said links being arranged in pairs in the respective sections, an end of each pair of links in a section being juxtaposed with each other and serving as spacers between ends of companion links of pairs of links in adjoining sections.
- 25 2. A mat formed of assemblies of obliquely disposed pairs of links arranged in rows transverse and longitudinally of the mat, the respective links of each pair being inclined
- 30 in opposite directions alternately in the respective transverse rows, and in corresponding directions in the respective longitudinal rows, and rods extending transversely through the mat for connecting the links
- 35 together.
3. A mat formed of end and intermediate sections longitudinally of the mat, each section comprising a plurality of link elements with apertures at the opposite ends thereof,
- 40 rods extending through said apertures to connect the links in the respective sections, one rod of each end section and both rods of the intermediate sections serving to hingedly connect the sections together, spacing ele-
- 45 ments mounted upon the other rod of each end section, said spacing elements and the links being arranged in close laterally abutting relation at one end upon the various rods and in respect to each other so as to dispose
- 50 the links in angular relation to both the longitudinal and transverse axes of the mat.

Signed at Seattle, Washington, this 28th day of September, 1928.

HAROLD W. HOLLENBECK.
